(57) **CLAIM**

The ornamental design for an operator compartment step arrangement for a materials handling vehicle, as shown.

DESCRIPTION

FIG. 1 is a perspective view of an operator compartment step arrangement for a materials handling vehicle taken from the right rear showing our new design;

FIG. 2 is a perspective view of the operator compartment step arrangement of FIG. 1 shown on an enlarged scale;

FIG. 3 is a plan top view of the operator compartment step arrangement of FIGS. 1 and 2;

FIG. 4 is an elevational rear view of the operator compartment step arrangement of FIGS. 1 and 2;

FIG. 5 is an elevational left side view of the operator compartment step arrangement of FIGS. 1 and 2; and,
FIG. 6 is an elevational right side view of the operator compartment step arrangement of FIGS. 1 and 2.
